DESIGN FOR A SHAKER FOR SALT OR PEPPER

Agnes Gail McClelland, Oklahoma City, Okla.

Application June 23, 1941, Serial No. 101,631

Term of patent 7 years

To all whom it may concern:

Be it known that I, Agnes Gail McClelland, a citizen of the United States, residing at Oklahoma City, in the county of Oklahoma, and State of Oklahoma, have invented a new, original, and ornamental Design for a Shaker, for Salt or Pepper, of which the following is a specification, reference being had to the accompanying drawing, forming part thereof.

In the drawing:

Fig. 1 is a top plan view of a shaker, for salt or pepper, showing my design;

Fig. 2 is a top perspective view; and

Fig. 3 is an elevational view thereof.

The dominant feature of my design resides in the portion shown in full lines.

I claim:

The ornamental design for a shaker, for salt or pepper, as shown and described.

AGNES GAIL McCLELLAND.
